UNITED STATES PATENT OFFICE.

LUCIA D. HAUBNER, OF NEW YORK, N. Y.

DESIGN FOR GIMP.

SPECIFICATION forming part of Design No. 16,651, dated April 20, 1886.

Application filed March 11, 1886. Serial No. 194,694. Term of patent 3½ years.

To all whom it may concern:

Be it known that I, LUCIA D. HAUBNER, of the city, county, and State of New York, have invented a new and original Design for Gimp, 5 of which the following is a full, clear, and exact description, reference being had to the accompanying illustration, making part of this specification.

The leading feature of my design consists 10 in parallel spiral lines in relief on the face of the gimp, and in lines at right angles to and intersecting the spiral lines, thus forming rectangular fields.

In the gimp A B are parallel spiral lines 15 arranged in two pairs, the spirals of the pairs being in opposite directions.

C are lines extending across the spiral lines B at right angles, and forming rectangular fields.

D represents the border of the gimp. 20

Having thus described my design, I claim as new and desire to secure by Letters Patent—

The design for a gimp herein shown and described, the same consisting of the borders along the edges of the gimp, a series of spiral 25 lines in relief on the face of the gimp and between the borders, and transverse lines extending between the borders over the longitudinal and spiral lines, said spiral lines occupying the entire space between the borders, 30 substantially as shown and described.

In testimony that I claim the foregoing as my invention I have signed it this 10th day of March, 1886.

LUCIA D. HAUBNER.
